MAIL HOLDER OR THE LIKE

Clifford R. Schaible, 21 Walnut Lane,
Dayton, Ohio 45419

Filed Feb. 12, 1968, Ser. No. 10,543

Term of patent 14 years

Int. Cl. D19—02

U.S. Cl. D74—9

FIG. 1

FIG-4

FIG. 1 is a perspective view of a mail holder or the like and showing my new design;

FIG. 2 is a side view of the mail holder of FIG. 1;

FIG. 3 is a bottom view thereof;

FIG. 4 is a top plan view thereof;

FIG. 5 is an end view looking from right to left in FIG. 2; and

FIG. 6 is an end view looking from left to right in FIG. 2.

I claim:

The ornamental design for a mail holder or the like, substantially as shown.
